UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

COMPENSATING DEVICE FOR OIL-PUMP COUNTERS, ETC.

Application filed June 15, 1925. Serial No. 37,363.

This invention relates to compensating devices for oil pump counters of the general type shown in Letters Patent of the United States, Nos. 1,524,601, 1,524,602 and 1,524,607 all dated January 27, 1925, and more particularly to compensating devices shown in Letters Patent of the United States No. 1,531,823, dated March 31, 1925, in which compensation is secured through the adjustment of the fulcrum of one of two oscillating levers, one of which is actuated with the pump while the other is actuated by the first and is in operative relation with the counting mechanism or register by which the delivery of oil or other liquid is registered. In the embodiment of the present invention there are also two oscillating levers, one of which is actuated with the pump while the other is in operative relation with the counting mechanism or register but provision is made in the connection between the two oscillating levers whereby, through adjustment, the compensation required by reason of inaccuracies in the particular pump with which the register is connected or by reason of variations in the delivery of the pump due to other causes, is effected.

The invention will be described more fully hereinafter with reference to the accompanying drawing in which it is illustrated and in which:—

Figure 1 is a view in front elevation of a register with the compensating devices applied thereto, the register dial and casing being partly broken away to save space and the dial itself being broken off to permit the compensating devices to be shown.

Figure 2 is a view in sectional elevation on the plane indicated by the broken line 2—2 of Figure 1.

Figure 3 is a detail view in horizontal section on the plane indicated by the broken line 3—3 of Figure 1.

Figure 4 is a detail view illustrating a detail of the connection between the oscillating levers.

In the embodiment of the invention illustrated, the dial a , pointer a^1 , the pointer supporting shaft a^2 and the totalizing counter a^3 , together with other parts hereinafter mentioned, are supported by a suitable casing b . The pointer a^1 and the totalizing register a^3 are actuated, in the operation of the pump, through a shaft c in operative relation with

a moving part of the pump mechanism, not necessary to be shown, the shaft c receiving a rotary oscillating movement. The shaft c carries a gear c^1 which meshes with a gear segment or toothed oscillating lever d pivotally mounted on a stud d^1 supported by the casing b . The segment d has an arm d^2 which is connected at its end by a link d^3 with an intermediate lever d^4 pivotally supported on a stud d^5 . The lever d^4 is also connected by a link e with an arm e^1 of a gear segment or toothed oscillating lever e^2 , which may be mounted on the stud d^1 , which supports the similar segment d . The arm e^1 is slotted longitudinally, as at e^3 , to permit the connection of the link e therewith to be adjusted, a suitable clamping nut e^4 being provided to secure the connection in adjusted position.

The segment e^2 engages a gear f which is fixed on the supporting shaft a^2 , the latter being mounted in a sleeve bearing a^4 which is supported by the frame a^5 . The shaft a^2 has secured thereon one member g of a clutch, preferably a ball clutch, the other member g^1 of which is frictionally engaged with the pointer a^1 , through the pressure of the spring plate g^2 . A retaining clutch g^3 is mounted on a sleeve bearing a^4 to prevent backward movement of the clutch member g^1 .

The clutch member g^1 may also be engaged operatively with the totalizing register a^3 , as through gears g^4 and h and coupling h^1 .

It will now be understood that when rotary oscillating movement is imparted to the shaft c , the gear segment d will be oscillated and, through the link d^3 , lever d^4 and link e , will oscillate the gear segment e^2 through an angle of oscillation which can be varied with respect to the angle of oscillation of the gear segment d , through adjustment of the connection at e^3 , e^4 between the two segments, so as to compensate, as may be required, for the inaccuracies of the pump or other conditions, the compensation being adjusted to suit the particular pump with which the register is used through adjustment of such connection as indicated. Through the connection from the gear segment e^2 to the registering or counting mechanism the operation of the latter will likewise be modified so as to compensate, as may

be required, for the inaccuracies of the pump or other conditions which make such compensation desirable.

I claim as my invention:—

- 5 1. The combination of a counting mechanism for a pump, a rotary oscillating gear actuated with the pump, an oscillating gear segment engaged with the gear, a second oscillating gear segment in operative relation with the counting mechanism, and adjustable connections between said gear segments whereby the second gear segment is oscillated by the first gear segment and the angular movement of the second gear segment may be varied with respect to the angular movement of the first gear segment.
- 10
- 15

2. The combination of a counting mechanism for a pump, a rotary oscillating gear actuated with the pump, an oscillating gear segment engaged with the gear, a second oscillating gear segment in operative relation with the counting mechanism, an intermediate lever, and separate link connections from the intermediate lever to the segments, the connection of the link to one of the segments being adjustable to vary the angular movement of one segment with respect to the angular movement of the other segment.

This specification signed this 2nd day of June A. D. 1925.

CURTIS HUSSEY VEEDER.
